FIG. 1

FIG. 2

FIG. 1 is a perspective view of a control knob for a thermostatic valve or the like showing our new design; and

FIG. 2 is an elevational view taken from one side thereof with a portion broken away for convenience of illustration.

The broken line representation of indicia in FIGS. 1 and 2 is for purposes of illustration only.

We claim:

The ornamental design for a control knob for a thermostatic valve or the like, substantially as shown and described.
